Patented Oct. 30, 1973

228,976

BEVERAGE DISPENSING TANK OR SIMILAR ARTICLE

Calvin L. Wilson and John H. Fox, Jr., Richmond, Va.,
assignors to Reynolds Metals Company, Richmond, Va.

Filed Dec. 28, 1971, Ser. No. 213,232

Term of patent 14 years

Int. Cl. D15—08

U.S. Cl. D94—3 B

FIG. 1

FIG. 2

FIG. 3

FIG. 4

FIG.5

FIG.6

FIG. 7

FIG. 1 is a front perspective view of a beverage dispensing tank or similar article embodying our new design;

FIG. 2 is a front elevational view;

FIG. 3 is a side elevational view;

FIG. 4 is a side elevational view partly in section taken on the line 4—4 of FIG. 5;

FIG. 5 is a top plan view;

FIG. 6 is a bottom plan view; and

FIG. 7 is a rear elevational view.

We claim:

The ornamental design for a beverage dispensing tank or similar article, as shown.
